INDUCTION HEATING DEVICE

Edward H. Dehn, Oil City, Pa., assignor to United States Steel Corporation, a corporation of New Jersey
Filed Jan. 4, 1961, Ser. No. 89,628
4 Claims. (Cl. 219—10.79)

This invention relates to an improved induction heating device.

Although my invention is not thus limited, the device is particularly useful in heat-treating ball valve cages used in oil well pumps, for example as shown in Neilsen Patent No. 2,294,568. A conventional ball valve cage includes a plurality of internal longitudinal ribs for guiding the ball closure member, and respective fingers at one end of each rib for limiting relative movement of the ball in that direction. Such cages are of small size, commonly having an inside diameter of less than 2 inches. Desirably the ribs and fingers are hardened to resist wear which results from constant movement of the ball, but the remainder of the cage is left unhardened to promote toughness. It is known to employ induction heating devices for selectively heat-hardening the ribs and fingers, but previous devices with which I am familiar heat only one rib and finger at a time. In structures of such small size, it has been considered impractical to heat a plurality of ribs and fingers simultaneously for the reason that intermediate adjacent portions of the structure become overheated and lose toughness.

An object of the present invention is to provide an improved induction heating device which simultaneously heats a plurality of selected portions on the interior of a small metal article without overheating intermediate adjacent portions.

A further object is to provide an improved induction heating device which enables all ribs and fingers of a ball valve cage to be heated for hardening in a single operation without adverse effects on the remainder of the cage structure.

A further object is to provide a device which has the foregoing improved characteristics and is of simple construction readily used in existing manufacturing processes.

In accomplishing these and other objects of the invention, I have provided improved details of structure, a preferred form of which is shown in the accompanying drawings, in which:

FIGURE 1 is a perspective view, with parts broken away, of my improved heating device;

FIGURE 2 is a cross section of the device on line II—II of FIGURE 1;

FIGURE 3 is an enlarged longitudinal sectional view of a ball valve cage of the type with which I can use my heating device; and

FIGURE 4 is a cross section of the cage on line IV—IV of FIGURE 3.

As FIGURES 1 and 2 show, my induction heating device includes a substantially cylindrical core 10 formed of a non-conducting ferromagnetic material. Such materials are available commercially, and consist of fine magnetic particles dispersed in a heat-resistant, electrically insulating binder, commonly plastic. An electrically conductive stem 12 is fixed to the core and extends upwardly therefrom. At least the upper portion of the stem is tubular, having a bore 13. An electrically conductive fitting 14 is fixed to the side of the stem above the core. One end of a continuous length of copper tubing 15, preferably of square cross section, is joined to the fitting 14, which also provides communication between the bores of the tubing and stem. Tubing 15 has a convolution 16 which extends downwardly within a longitudinal groove 17 in the circumferential face of the core, forms an enlarged loop 18 at the bottom edge of the core, and thence

2

extends upwardly within groove 17 back to the top of the core. Next tubing 15 extends across the top of the core to one or more additional circumferentially spaced grooves 17a and 17b, and it has convolutions which lie within these additional grooves with loops at the bottom, similar to the arrangement illustrated for groove 17. The other end of tubing 15 is connected to a tubular auxiliary stem 19 of electrically conductive material. Insulating inserts 20 separate the two lengths of tubing 15 which make up each convolution 16, and an insulating sheath 21 covers the entire core and tubing to prevent direct shorts. I connect stems 12 and 19 to a suitable high frequency A.-C. source and also to suitable means for circulating water through the stems and tubing 15.

The particular induction heating device illustrated is designed for use with a valve cage constructed as shown in FIGURES 3 and 4. This cage has three longitudinal ribs 22, 22a and 22b spaced 120° apart around its inner circumference. Respective integral fingers 23 are formed at one end of each rib. To heat-harden the ribs and fingers, I insert the device within the cage and apply current to the stems 12 and 19 and also circulate water therethrough to prevent overheating the tubing 15 and core 10. Each convolution 16 overlies a rib 22, 22a or 22b, and each loop 18 overlies a finger 23. The non-conducting magnetic core 10 acts as an intensifier and is essential to attain efficient heating. The heating effect is concentrated at the ribs and fingers, which quickly reach critical temperatures for hardening, while intermediate adjacent portions of the cage structure are not overheated. Following a brief heating step, I remove the device and quench the cage in any suitable known medium.

From the foregoing description, it is seen that my invention affords a simple device for inductively heating a plurality of selected portions of the interior of a small metal article. The particular valve cage illustrated is only one example of the sort of article with which I can use the device. For other articles it is only necessary to construct the device of a size to fit the article and with the convolutions of the current carrying tubing matching the portions to be heated. In simultaneously heating all the portions to be hardened, I achieve a further advantage over heating them one at a time in that I do not destroy the hardening attained on one portion when heating another portion. I believe I have achieved a surprising and unexpected result in locally heating selected areas within a small confined space without encountering canceling effects.

While I have shown and described only a single embodiment of my invention, it is apparent that modifications may arise. Therefore, I do not wish to be limited to the disclosure set forth but only by the scope of the appended claims.

I claim:

1. An induction heating device for simultaneously heating a plurality of selected portions on the interior of a small metal article without overheating intermediate adjacent portions, said device comprising a substantially cylindrical core of non-conducting ferromagnetic material, a conductor having a plurality of convolutions which extend along the sides of said core, each convolution being circumferentially spaced from adjacent convolutions to concentrate heating of the article to portions which the convolutions overlie, insulating material separating portions of said conductor making up the same convolution and covering said core and conductor, and means for applying high frequency electric current to said conductor.

2. An induction heating device for simultaneously heating a plurality of selected portions on the interior of a small metal article without overheating intermediate adjacent portions, said device comprising a substantially cylindrical core of non-conducting ferromagnetic material,

a tubular conductor having a plurality of convolutions which extend along the sides of said core, each convolution being circumferentially spaced from adjacent convolutions to concentrate heating of the article to portions which the convolutions overlie, insulating material separating portions of said conductor making up the same convolution and covering said core and conductor, means for applying high frequency electric current to said conductor, and means for circulating cooling water through the bore of said conductor.

3. An induction heating device for simultaneously heating a plurality of selected portions on the interior of a small metal article without overheating intermediate adjacent portions, said device comprising a substantially cylindrical core of non-conducting ferromagnetic material, an electrically conductive tubular stem fixed to an end of said core, a tubular conductor electrically connected at one end to said stem with its bore in communication with the bore of said stem, said conductor having a plurality of convolutions which extend in series along the sides of said core, each convolution being circumferentially spaced from adjacent convolutions to concentrate heating of the article to portions which the convolutions overlie, an electrically conductive tubular auxiliary stem electrically connected to the other end of said conductor with its bore in communication with the bore of said conductor, insulating material separating portions of said conductor making up the same convolution and covering said core and conductor, means for applying high frequency electric current to said stems, and means for circulating cooling water through the bores of said stems and said conductor.

4. An induction heating device for simultaneously heating a plurality of selected portions on the interior of a small metal article without overheating intermediate ad-

jacent portions, said device comprising a substantially cylindrical core of non-conducting ferromagnetic material having a plurality of circumferentially spaced longitudinal grooves in its sides, an electrically conductive tubular stem fixed to the top of said core, a tubular conductor electrically connected at one end to said stem with its bore in communication with the bore of said stem, said conductor having a plurality of convolutions which extend in series, each convolution lying within a different one of said grooves and having an enlarged loop at the bottom edge of said core, each convolution being circumferentially spaced from adjacent convolutions to concentrate heating of the article to portions which the convolutions overlie, an electrically conductive tubular auxiliary stem electrically connected to the other end of said conductor with its bore in communication with the bore of said conductor, insulating material separating portions of said conductor making up the same convolution and covering said core and conductor, means for applying high frequency electric current to said stems, and means for circulating cooling water through the bores of said stems and said conductor.
